(57) **CLAIM**

An ornamental design for a razor cartridge, as shown and described.

DESCRIPTION

FIG. 1 is a top, front and left side perspective of a razor cartridge showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is top plan view thereof;

FIG. 7 is a bottom plan view thereof; and,

FIG. 8 is a bottom, front and left side perspective view thereof.

The broken lines illustrate portions of the razor cartridge and form no part of the claimed design.
